UNITED STATES PATENT OFFICE.

ANE PIETER SCHAT, OF SAN FRANCISCO, CALIFORNIA.

ADJUSTABLE DAVIT.

Application filed October 26, 1918. Serial No. 259,790.

To all whom it may concern:

Be it known that I, ANE PIETER SCHAT, a citizen of Holland, residing at San Francisco, in the county of San Francisco and State of California, have invented certain new and useful Improvements in Adjustable Davits, of which the following is a specification.

My invention relates to devices for regulating the automatically operating davit which forms a part of the subject matter of my allowed application Ser. No. 230,106.

My object is to provide means for adjustably supporting the davit at different angles of inclination and in different planes, whereby to regulate its power of automatic movement and to predetermine the direction and limits of said movement.

An important feature of the construction shown in the drawings consists of a frame designed to be rotatably mounted on the deck of a ship and having for the davit a rocking support held at right angles to the plane of rotatable movement of the frame, with the davit rotatably mounted in said support.

The invention consists in certain novel features of construction and arrangement of parts as will be hereinafter described and claimed, reference being had to the accompanying drawings, in which:

Fig. 1 is a top plan view of my invention, with the davit proper shown in section; and,

Fig. 2 shows my device in side elevation.

The numeral 1 indicates the deck of a ship on which is mounted the frame A, having at its rear end the strong leg or standard 2, and at its forward end the two legs 3 spaced well apart from each other and connected together at their upper ends by the integral cross-bar 4, which in turn is connected with the rear standard 2 by the longitudinal bars 5 which are parallel with each other and preferably integral with the cross-bar 4 and the rear post or leg 2. The forward ends of the longitudinal bars 5 are also integrally connected with the rear post 2 by the downwardly and rearwardly extending flanges or plates 6 which are connected together at their bottoms by the bottom 7 of the frame which may be formed integral with them if desired.

Extending rearwardly from the lower

end of the standard 2 is the strong semicircular flange 8, and extending forwardly from the lower ends of the front standards or legs 3 and the parallel plates 6, is the integral segmental flange 9. The flange 8 at the rear end of the frame is provided with a strong pivot 10 securely anchored in the deck of the ship and upon which the frame A rotates; while the segmental flange 9 at the forward end of the frame is provided with a segmental slot 11 struck from the pivot point 10 at the rear end of the frame. A threaded bolt 12 extends upwardly through this slot from the deck of the ship and is provided with a nut 13 having an operating handle 14.

The frame is provided at its bottom between the two parallel plates 6 with a longitudinally extending rack 15, shown in dotted lines in Fig. 2, and mounted on this rack is a quadrant 16 adapted to be rocked back and forth thereupon. The quadrant is snugly received at its lower side between the two plates 6, and at its top between the two longitudinal bars 5, whereby it is suitably guided in its rocking movement.

The lower portion of the davit 17 is rotatably mounted in this quadrant which is provided at its upper end with a bore 18 through which the davit passes.

At the extreme top of the frame I provide the guide-bars 19 which extend from the transverse bar 4 to the rear standard 2, being rigidly secured to these parts. These bars 19 are located immediately above the longitudinal bars 5 and extend parallel therewith, the bars 5 being also guide-bars adapted to cooperate with said bars 19 to form guides for the guide-block 20, which is provided at its forward end with two parallel apertured ears 21 adapted to receive between them the cooperating apertured lug or ear 22 extending rearwardly from the top of the quadrant 16, said lugs being operatively connected together by the pin 23.

The screw bar 24 passes through the upper end of the standard 2 with which it has threaded engagement, and is suitably connected at its inner end with the guide-block 20 which is adapted to be moved back and forth by said screw bar, the bar being provided on its outer end with the hand wheel 25 for convenient manipulation.

From the construction shown, it will be seen that the davit will tend to automati-

cally swing around by gravity and come to rest in a plane extending longitudinally of the frame whenever the lower end of the davit is inclined toward one end or the other thereof, and the greater the inclination of the davit the stronger will this tendency be. It is further manifest that since the frame is rotatable on the pivot 10, it may be caused to extend longitudinally toward any given point of the compass; and thereby the point toward which the davit shall tend to move and come to rest can be accurately predetermined.

Hence it will be seen that the combined effect of the rotary movement of the frame and the rocking movement of the davit will be to impart to the davit a greater or less tendency, as may be desired, to automatically swing to any desired point of the compass.

The frame is rotatably pivoted at its rear end instead of at its forward end, because ordinarily the davit will swing out over the forward end, and it is therefore desirable that that should be the movable end of the frame because the weight of the davit will tend to hold that end down in firm frictional engagement with the deck of the ship, and the greater the weight on the davit the more firmly will it be held, even though, under peculiar stress or excitement, the securing nut 13 might not have been screwed down as firmly as it should have been. On the other hand, it will be seen that the load on the davit will tend to move the rear end of the frame upwardly—a movement which if permitted through possible carelessness or oversight might prove disastrous. Therefore the frame is rotated from its rearward end and is permanently locked in rotatable engagement with the ship's deck at that point.

Of course the davit can be caused to incline toward the rear end of the frame if desired, but, in cases where uses of that kind are contemplated, the rear end of the frame should be provided with a transverse bar having legs at its ends similar to the transverse bar 4 and the legs 3 at the forward end of the frame, to better support the lateral strain imposed upon the frame as the davit swings its load around. By this arrangement the rear end of the frame would be supported against lateral strain just as the forward end is now supported.

Of course it is not compulsory that the pivot upon which the frame rotates should be at one end or the other, since it may be at any point between the two ends of the frame. In cases where the frame is to be frequently turned around to any considerable degree the pivot point can be at the centre, which will permit the frame to turn around its centre, thus requiring much less space than for it to swing around its pivot

point at one end as it now does. However, it is thought that for ordinary uses the arrangement here shown is best.

It may here be observed that, since the davit can be caused to incline toward either end of the frame, in no case would the frame have to be rotated through more than 180 degrees, or half a circle, in order to impart to the davit a tendency to move to any point of the compass.

As to the operation of my device it is only necessary to add to the foregoing that when it is desired to swing automatically toward any given direction, the forward end of the frame is swung around to cause the frame to extend longitudinally in that direction; or in other words, the frame is swung around with its forward end facing in that direction. The frame is then secured in that position by a proper turn of the nut 13.

To increase or diminish the power of automatic movement of the davit toward the desired point it is now only necessary to increase or diminish the angle of inclination of the lower portion of the davit by properly turning the regulating screw bar 24, which operates through the guide-block 20 and the quadrant 16.

Since in my device the screw bar 24 is not designed to lift the davit but simply to adjust it, this bar only needs to be short, which considered in connection with other features of the device, gives a very neat, compact construction, while at the same time adapting the davit for universal movement with a wide range of power to move automatically in any direction desired.

It will be noticed that my frame, though not very heavy is yet an exceedingly strong, durable, and—as has already been stated—compact construction admirably adapted to withstand the sudden strains often imposed upon devices of this character.

Having now disclosed the principles of my invention, and shown one method of practically embodying these principles, I yet do not wish to be limited to the single construction herein shown, but desire protection on all that comes clearly within the spirit and scope of my invention.

What I claim as new and desire to secure by Letters Patent is:—

1. A device of the character described, comprising a davit; and a movable support for the same mounted on the deck of the ship, said support being pivoted at its inner end to the deck with its outer end adapted to swing horizontally outward and inward around said pivotal centre, to cause said support to extend at any desired angle relatively to the longitudinal extent of the ship, said horizontally swinging end of the support being provided with means for holding the support in its adjusted positions,

and having bearings for holding the davit to rotate on its longitudinal axis in an inclined position, to impart to the davit a tendency to rotate by gravity in the direction of its 5 inclination, the inclination of said bearings being in a vertical plane extending longitudinally of said support; whereby to adjustably support the davit at different distances from the sides of the ship, and to 10 vary the angle, relatively to the longitudinal extent of the ship, to which the davit will tend to rotate by gravity.

2. A device of the character described, comprising a rotatable frame adapted to be 15 mounted on the deck of a ship; a rocking member mounted in the frame; a davit mounted in the rocking member to rotate on its longitudinal axis therein; and means for adjusting the rocking member to vary 20 the angular relation of the davit to the frame.

3. A device of the character described, comprising a frame adapted to rotate laterally on the deck of a ship, and having a 25 longitudinally extending rack; a toothed quadrant mounted to rock on said longitudinal rack; a davit having its upper and lower portions disposed at an angle to each other and with its lower portion mounted to 30 rotate on its longitudinal axis in said quadrant; and means for adjusting the quadrant to vary the angular relation of the lower

portion of the davit to the longitudinal extent of the frame.

4. A device of the character described, 35 comprising a longitudinally extending frame having a supporting standard at its rear end and a broad support at its forward end extending at right angles to the longitudinal extent of the frame, said frame being 40 adapted to be pivotally connected at its rear end to the deck of the ship to adapt the frame for horizontal adjustment thereon; a flange at the forward end of the frame provided with a segmental slot; means co- 45 operating with said slot and flange for holding the frame in adjusted position on the deck of the ship; a toothed rack extending centrally from the forward to the rearward end of the frame at the bottom thereof; a toothed quadrant mounted to rock on said rack; a davit mounted in said quadrant and adapted to rotate on its longitudinal axis 50 therein; an adjusting screw centrally located at the rear end of the frame for controlling 55 said quadrant to vary the angular relation of the davit to the longitudinal extent of the frame; a guide-block connecting said screw and quadrant; and guides at the top and bottom of the frame for the quadrant and guide-block. 60

In testimony whereof I affix my signature.

ANE PIETER SCHAT.
